UNITED STATES PATENT OFFICE

147,873

DESIGN FOR A COMBINATION CHAIR AND TABLE OR LIKE ARTICLE

Rudolph G. Schneider, Houston, Tex.

Application January 5, 1946, Serial No. 125,309

Term of patent 14 years

(Cl. D15—1)

To all whom it may concern:

Be it known that I, Rudolph G. Schneider, a citizen of the United States, residing at Houston, in the county of Harris and State of Texas, have invented a new, original, and ornamental Design for a Combination Chair and Table or Like Article, of which the following is a specification, reference being had to the accompanying drawing, forming part thereof.

Figure 1 is a side elevational view of a combination chair and table or like article, showing my new design.

Figure 2 is a front elevational view of the same observing Figure 1 is a direction from right to left.

Figure 3 is a rear elevational view.

Figure 4 is a bottom plan view of the same.

I claim:

The ornamental design for a combination chair and table or like article, substantially as shown.

RUDOLPH G. SCHNEIDER.
